US00D964351S

(12) **United States Design Patent** (10) **Patent No.:** **US D964,351 S**
(45) **Date of Patent:** **** Sep. 20, 2022**

(54) **ELECTRONIC DEVICE**(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)(***) Term: **15 Years**(21) Appl. No.: **29/689,683**(22) Filed: **May 1, 2019****Related U.S. Application Data**

(63) Continuation of application No. 29/586,519, filed on Dec. 5, 2016, now Pat. No. Des. 864,950, which is a continuation of application No. 29/493,571, filed on Jun. 11, 2014, now Pat. No. Des. 773,453, which is a continuation of application No. 29/423,180, filed on May 29, 2012, now Pat. No. Des. 707,223.
